UNITED STATES PATENT OFFICE.

JOHN L. CREVELING, OF NEW YORK, N. Y., ASSIGNOR TO SAFETY CAR HEATING & LIGHTING COMPANY, A CORPORATION OF NEW JERSEY.

ELECTRIC-LIGHTING SYSTEM.

No. 920,827.

Specification of Letters Patent.

Patented May 4, 1908.

Application filed May 28, 1908. Serial No. 435,376.

To all whom it may concern:

Be it known that I, JOHN L. CREVELING, a resident of New York, in the county and State of New York, have invented a certain new and useful Improvement in Electric-Lighting Systems, as set forth in the annexed specification and drawing, forming a part thereof.

My invention pertains to that class of electric lighting systems as usually employed for the lighting of railway cars in which a generator driven at variable speed furnishes current for operating lamps or other translating devices and charging a storage battery which furnishes the current to the lamps or other translating devices when the generator is inoperative.

My invention has for its particular object to provide means whereby the output of the generator shall be regulated in a desired manner, and also means whereby the voltage impressed upon the lamps or other translating devices shall be held practically constant regardless of the speed of the train or the condition of charge of the storage battery.

In the drawing (1) represents an ordinary dynamo or generator driven at variable speed as for instance a generator deriving its motion from the motion of a car.

(2) represents the ordinary field winding of the generator in this instance shown as a plain shunt, the circuit of which is in series with the resistance device indicated at (3), in shunt with which may be placed the resistance (4). The variable resistance (3) may be of any desired type and in this instance is shown as of the carbon disk variety for sake of simplicity and so arranged that the spring (5) adjustable as by the screw (6) tends to press the disks together through the instrumentality of lever (7) thereby lowering the resistance of the field circuit.

The lever (7) is provided with the extension (8) carrying the hinged extension (9) pivoted as at (10). The members (8) and (9) carry the posts (11) the motion of which serves to operate a resistance device (12), in this instance shown as of the ordinary carbon disk type, so arranged that a spring (13) adjustable as by the screw (14) tends to lower the resistance of the same as by compressing the disks. Pull upon the link (15) will tend to lessen the pressure on the disks (12) and by proper design of springs (5) and (13) motion of the link (15) may be made to increase

the resistance of the device (12) until the adjusting screw (16) shall come in contact with the lever (8) before any appreciable change is made in resistance of device (3).

To the link (15) is attached the core (17) of the solenoid (18) provided with a coarse winding in series with the generator as by leads (19) and (20). The other side of the generator is connected by lead (21) to one terminal of the automatic switch (22) from the other terminal of which the main (23) is led to one terminal of the storage battery (24) and one terminal of the resistance (25) from the other terminal of which is led lamp or translating main (26). The lamps or other translating devices (27) are placed across the mains (20) and (26) and the storage battery (24) across mains (20) and (23).

The resistance device (12) serves as a shunt to part of the resistance (25) by its connection through wires (28) and (29). (30) is a resistance device connected in shunt with the other portion of the resistance (25) as by wires (31) and (32), and in this instance is shown as of the ordinary carbon disk type in which the pressure of the spring (33) adjustable as by the screw (34) tends to compact the carbons so as to reduce the resistance thereof. Pull upon the link (35) tends to move the lever (36) in such manner as to increase the resistance of the device (30). The lever (36) is attached to the core (37) of the solenoid (38) which has a fine winding in shunt across the battery as by wires (39) and (40). The lever (36) is provided with an adjusting screw (41) so arranged that when the lever (36) shall have received a predetermined movement screw (41) will have come in contact with the lever (7) so that further movement of the lever (36) will cause further movement of the lever (7) thereby assisting in the increase of resistance in the resistance device (3).

The operation of my improved system of electric lighting is substantially as follows: starting with the generator at rest and the various devices in the positions shown in the drawing. If the car starts to move, the armature of the generator (1) will revolve and current will tend to flow through the field winding (2) shunt (4) and resistance (3) back to the generator. This will cause the field to build up in a well known manner, and if the speed increase sufficiently to raise the voltage of the generator to that of the bat-

tery (24) the switch (22) will close and complete the main circuit in a well known manner. Detail of the switch (22) is omitted in this application as its particular construction forms no part of my present invention and a good type of switch for use in this system is shown and described in Patent #707,763 granted to me August 26, 1902. Further increase in the speed will cause current to flow from the generator to the battery (24) and lamps or other translating devices (27) returning to the generator through the lead (20), solenoid (18) and lead (19). As this current gradually increases, the solenoid (18) by attracting its core (17) against the action of the spring (13) gradually increases the resistance (12) until the same may practically break the circuit through (28) and (29) thereby inserting into the lamp circuit that portion of the resistance (25) which is normally what might be considered shunted out by the resistance devices (12) when the generator is at rest. By proper adjustment of the spring (13) the resistance device (12) may be caused to insert resistance into the lamp circuit to compensate for the rise in voltage necessary to raise the generator output from zero to a desired maximum, and when this maximum is reached any further action of the solenoid (18) due to any increase in current will cause a further movement of the core (17) so as to move the lever (7) against the action of spring (5) and increase resistance (3) and thereby cut down the current in the field coil (2) and in that way prevent any appreciable rise in the output of the generator upon further increase in speed. If the batteries have been more or less discharged their voltage will remain constant for some time under the above conditions and then if their charging continues will rise appreciably and if the solenoid (38) be properly designed and the spring (33) properly adjusted, as this rise above the normal voltage begins to take place the solenoid (38) will move its core (37) so as to move lever (36) against the action of the spring (33) and thus increase the resistance in the lamp or translating circuit in a well known manner, and will continue to increase this resistance so long as the voltage across the batteries continues to increase.

By proper adjustment of the screw (41) the same may be made to engage the lever (7) so that when the voltage across the battery (24) has reached a predetermined limit, which we may call the normal charged voltage then any further increase in voltage will cause the solenoid (38) to assist the solenoid (18) in moving the lever (7) so as to increase the resistance of the device (3) and cut down the output of the generator or the screw (41) may be backed out so as not to engage the lever (7) in any of its operative positions if desired and the two solenoids will then per-

form their functions independently as above outlined in the same manner as if the said connection between the levers (7) and (36) were entirely omitted. The inter-action between solenoids (18) and (38) in controlling the output of the generator is not claimed in this application as the same forms the subject matter of a divisional application filed by me. Now if the generator slow down to such speed that its output shall decrease then solenoid (18) will allow the core (17) to rise under the influence of spring (5) and cut resistance out of the field circuit and tend to hold the output constant. Further decrease in speed will cause this action to continue until the time is reached when there will be no further movement of the lever (7), and then further decrease in speed will cause a decrease in the resistance (12) in such manner as to compensate for the drop in voltage in the lamp circuit caused by the generator output falling until the point is reached when the voltage of the generator and battery are practically equal, at which point the switch (22) may open leaving the lamp load entirely on the storage battery, which if above the normal voltage will supply current to the lamps through the resistance (25) and resistance (30) at the normal voltage. Now if this load be left upon the battery for any appreciable time this voltage will come down to the normal and as it does the solenoid (38) will allow its core (37) to rise under the action of spring (33) and gradually shunt out that portion of the resistance (25) which had previously been inserted to make up for the increase in battery voltage.

In the ordinary operation of this system the resistance (12) operates merely to compensate for the rise in voltage upon the translating circuit which is caused by the rise in voltage of the generator necessary to bring its output from zero to a desired maximum and the reverse, and the resistance (30) compensates for the rise in voltage above the normal due to the continued charging of the battery and under ordinary conditions produces little or no effect in the lamp circuit caused by the fluctuations of current due to changes of the generator output between its predetermined limits of operation.

I do not wish in any way to limit myself to any of the exact constructions or details shown in the attached drawing which is a mere diagrammatic representation of an electric system embodying the essentials of my invention and it is quite obvious that wide departure in forms of construction may be taken without departing from the scope of my invention.

Having thus described my invention what I consider novel and desire to protect by Letters Patent is as set forth in the following claims:

1. An electric lighting system comprising

hending a generator, a storage battery and lamps or other translating devices combined with means for governing the voltage on the translating devices to compensate for a rise 5 in voltage across the generator mains necessary to bring the generator to full load, means for maintaining said load practically constant throughout certain changes in speed and means governing the voltage upon 10 the translation devices to compensate for the rise in voltage across the battery due to continued operation of the generator.

2. An electric lighting system comprehending a generator, a storage battery and 15 lamps or translating devices combined with means maintaining the generator output constant throughout changes in speed, means dependent upon the generator output for governing the voltage upon the lamps or 20 translating devices and means dependent upon the voltage of the battery governing the voltage upon the lamps or translating devices.

3. An electric lighting system comprehending a generator, a storage battery and a 25 translation circuit combined with means whereby an increase in output of the generator tends to increase the resistance in the translation circuit and means whereby an increase in voltage across the battery tends to 30 decrease the voltage of the translating circuit.

4. An electric lighting system comprehending a generator, a storage battery and 35 lamps or other translating devices combined with a magnet in series with the generator,

means operated by said magnet to increase the resistance of the translation circuit and also to govern the output of the generator, a magnet in shunt to the storage battery and 40 means whereby said magnet may alter the voltage upon the lamps or translating devices.

5. The combination with a generator, a main circuit a storage battery, a work circuit 45 connected therewith and a field energizing coil for said dynamo, of a magnet the field of which is a function of the current generated, actuating means whereby said magnet varies the voltage upon the work circuit, a magnet 50 whose operation is a function of the voltage of the storage battery and operating means whereby the voltage upon work circuit is altered thereby.

6. In an electric lighting system comprehending a generator, a storage battery, a work circuit and a generator field circuit the combination with means varying the current in the field circuit and a plurality of means altering the voltage upon the work circuit of 55 means the effect of which is a function of the current generated and operating to actuate one of the voltage varying means and the field circuit varying means and electro magnetic means the effect of which is a function 60 of the voltage across the battery circuit operating another of the voltage varying means in the work circuit.
